GRINDING WHEEL AND TREATMENT
THEREOF

Nils Gunnar Anderson and Axel Fredrik Thure
Lofquist, Malmo, Sweden, assignors to Norton
Company, Worcester, Mass.

No Drawing. Application November 19, 1935,
Serial No. 50,568. In Sweden December 5,
1934

8 Claims. (Cl. 51—280)

The invention relates to grinding wheels and a treatment thereof to improve their quality.

One object of the invention is to provide a faster cutting grinding wheel. Another object of the invention is to provide a treatment which can be applied to already manufactured grinding wheels to increase the rate of cutting thereof. Another object of the invention is to provide an improved filler for a grinding wheel. Another object of the invention is to provide an improved snagging wheel. Another object of the invention is to provide an improved wheel for grinding stainless steel. Another object of the invention is to provide a treatment for wheels which shall improve their action in dry grinding. Another object of the invention is to provide a grinding wheel, and/or a treatment for a grinding wheel, which enables it to remove a greater amount of stock for a given amount of wheel wear than heretofore. Other objects will be in part obvious or in part pointed out hereinafter.

The invention accordingly consists in the features of construction, combinations of elements, and in the several steps and relation and order of each of said steps to one or more of the others thereof, all as will be illustratively described herein, and the scope of the application of which will be indicated in the following claims.

30 We provide a grinding wheel. The invention is not limited to any size, shape, or type of grinding wheel. We prefer to provide a relatively porous grinding wheel, such as one of the wheels bonded with any known vitrified or ceramic bond. Such a wheel may be made according to any known method. The wheel is completely formed or fired or the bond otherwise set prior to the treatment now to be described, so far as the preferred form of our invention is concerned.

Having formed the grinding wheel we make a solution, preferably a water solution, of a deliquescent salt. Any one of the chlorides, sulphides, nitrates, carbonates, or acetates which are deliquescent may be used. Excellent results have been achieved in practice from the use of zinc chloride, and calcium chloride, which is a somewhat cheaper salt and also highly deliquescent, may be used to great advantage.

50 The solution need not be a saturated solution but should be a strong solution. Other than that there is no critical point, as the object is to introduce a deposit into the wheel and whatever method introduces a substantial deposit

into the wheel is a good method in actual practice.

Having made the solution we place the grinding wheel in it, or pour it over the grinding wheel. Having thoroughly wet the grinding wheel with the salt solution, the excess over and above what remains by capillary action is removed by spinning the wheel. However, the wheel should be spun at a slow speed for a short time in order not to remove too much of the liquid. The wheel may then be allowed to dry 10 to some extent if desired. Usually the wheel still contains much moisture when it is used on account of the deliquescence of the salt.

The wheel may now be used for snagging 15 castings or for any other purpose where no supply of water is provided. When so used it is found that the wheel grinds as much as 66% faster than an untreated wheel of the same grade and structure otherwise. The wheel has a freer cutting action. While the treatment herein described increases the wheel wear somewhat, this increase is far less than the increase in the rate of cutting and consequently for a given amount of wheel wear there will be a greater 20 amount of material removed according to this 25 invention.

The wheel is also particularly useful in the cutting of stainless steel. It appears that the impregnation of the wheel with a deliquescent 30 salt to a certain extent reduces glazing. Probably also there is a lubricating action. But whatever the theory, and we do not wish to be held to the foregoing theories, greatly improved results are achieved.

It will thus be seen that there has been provided by this invention a method and an article in which the various objects hereinabove set forth together with many thoroughly practical advantages are successfully achieved. As various 40 possible embodiments might be made of the mechanical features of the above invention and as the art herein described might be varied in various parts, all without departing from the scope 45 of the invention, it is to be understood that all matter hereinbefore set forth is to be interpreted as illustrative and not in a limiting sense.

We claim:

1. Method according to the invention which comprises forming a grinding wheel including 50 completely setting the bond thereof, preparing a solution of a deliquescent salt, bringing the wheel and the solution together to impregnate the wheel with the solution, and spinning the wheel to remove excess solution.

2. Method according to claim 1 in which the wheel is treated with a deliquescent chloride.
3. Method according to claim 1 in which the wheel is treated with a zinc chloride.
4. As a new article of manufacture, a grinding wheel having in its pores a deposit of a deliquescent salt.
5. As a new article of manufacture, a grinding wheel having in its pores a deposit of a deliquescent chloride.
6. As a new article of manufacture, a vitrified
- ceramic bonded grinding wheel having in its pores a deposit of a deliquescent salt.
7. As a new article of manufacture, a vitrified ceramic bonded grinding wheel having in its pores a deposit of a deliquescent chloride.
8. As a new article of manufacture, a grinding wheel having in its pores a deposit of zinc chloride.

NILS GUNNAR ANDERSON.

AXEL FREDRIK THURE LOFQUIST.
